UNITED STATES PATENT OFFICE.

EMIL H. P. MEHL, OF JERSEY CITY, NEW JERSEY.

DESIGN FOR ORNAMENTATION OF LEATHER.

SPECIFICATION forming part of Design No. 15,473, dated October 21, 1884.

Application filed July 18, 1884. Term of patent 3½ years.

To all whom it may concern:

Be it known that I, EMIL H. P. MEHL, of Jersey City, in the county of Hudson and State of New Jersey, have invented and produced 5 a new and original Design for Ornamentation of Leather, of which the following is a full, clear, and exact description.

Reference is to be had to the accompanying drawing, forming a part of this specification, 10 and which fully illustrates my design.

The leading feature of my design for the ornamentation of leather consists in a continuous surface which presents the appearance of

closely-woven strips of pebbled leather, resembling basket-work, border-lines being represented on the edges of said strips. 15

I claim—

The design for the ornamentation of leather herein described, the same consisting of a continuous surface presenting the appearance of 20 closely-woven strips of pebbled leather, having border-lines, as shown.

EMIL H. P. MEHL.
